Specification for Design.

Patented Mar. 28, 1916.

Application filed July 21, 1915. Serial No. 41,193. Term of patent 7 years.

To all whom it may concern:

Be it known that we, HORACE D. BALL, JOHN I. FLOYD, and LEONARD S. CARR, citizens of the United States, residing at Beloit, in the county of Rock and State of Wisconsin, have invented a new, original, and ornamental Design for Casings for Direction-Indicators, of which the following is a specification, reference being had to the accompanying drawing, forming part thereof.

In the drawing—Figure 1 is a plan view of a casing for a direction indicator, showing our new design; and Figs. 2 and 3 are face and side views thereof, respectively.

We claim:

The ornamental design for a casing for a direction indicator, as shown.

HORACE D. BALL.
JOHN I. FLOYD.
